N,N - METHYL CYCLOHEXYL - 2 - ETHYL - 3,3 - DI-PHENYL - PROPENE - (2) - YL-AMINE AND THE SALTS THEREOF

Horst Eissler, Ludwigshafen, Mundenheim, Germany, assignor to Gebruder Giulini G.m.b.H., Ludwigshafen (Rhine), Germany, a corporation of Germany

No Drawing. Continuation of application Ser. No. 313,425, Oct. 3, 1963, which is a division of application Ser. No. 231,018, Oct. 16, 1962. This application Apr. 24, 1967, Ser. No. 634,430

Claims priority, application Germany, Oct. 19, 1961, G 33,376

Int. Cl. C07c 87/40; A61k 27/00

U.S. Cl. 260—295.5

1 Claim

ABSTRACT OF THE DISCLOSURE

Compounds of the formula:

wherein:

- (a) R₁ is alkyl having 2 to about 8 carbon atoms;
  - (b) R₂ and R₃ is each selected from the group consisting of lower alkyl and lower cycloalkyl;
- and medicinally acceptable salts thereof. The compounds are useful as vasopressor agents.

This application is a continuation of Ser. No. 313,425, filed Oct. 3, 1963, and now abandoned, which in turn is a divisional application of Ser. No. 231,018, filed Oct. 16, 1962, and now abandoned and replaced by Ser. No. 324,824, filed Nov. 19, 1963, which issued as Patent 3,345,411, Oct. 3, 1967.

This invention relates to the tertiary amines of 3,3-diphenyl propyl amine compounds of the formula

(I)

Wherein R₁ is alkyl, for example alkyl having up to 8 carbon atoms, preferably having 2-8 carbon atoms, for example ethyl, propyl, butyl;

R₂ and R₃ is each selected from the group consisting of alkyl and cycloalkyl, and preferably each is a lower alkyl or lower cycloalkyl and is a group as is conventionally present in organic amino compounds for therapeutic use and preferably containing up to about 6 carbon atoms, and each of the groups can be, for example, methyl, butyl, ethyl, propyl, isopropyl, isobutyl, secondary butyl, isoamyl, hexyl, isohexyl, and cyclohexyl.

Preferred products of formula (I) are those wherein R₁ is ethyl, propyl or butyl, especially ethyl.

Particular compounds found to be well suited for the purposes of the invention are: N,N-dimethyl-2-ethyl-3,3-diphenyl-propene-(2)-yl-amine, N,N-dipropyl-2-ethyl-3,3-diphenyl-propene-(2)-yl-amine, N,N-methyl cyclohexyl-2-ethyl-3,3-diphenyl-propene-(2)-yl-amine, and medicinally acceptable acid addition salts of these compounds or other medicinally acceptable salts.

The compounds of the above formula valuable therapeutic properties which render them useful as vasopressors and in particular for increasing blood pressure, stimulating the heart muscle, accelerating the heart rate and

2

increasing cardiac output. Of outstanding importance is that they diminish or eliminate the undesirable depressive side effects of morphine or respiration. The compounds can be used in the form of medically acceptable acid addition salts. The vasopressor effect is accomplished by administration of a therapeutic amount of the compound used.

ethyl-3,3-diphenyl-propene-(2)-yl-amine, and medicinally acceptable acid addition salts with hydrochloric, hydrobromic, or hydroiodic acid. Acid addition salts are preferred. The salts are crystalline solids which are soluble in water and therefore constitute an advantageous embodiment of this invention. The disclosed organic bases form salts with a variety of inorganic and organic acids conventionally used for therapeutic application or organic amino or imino bases and including hydrochloric, hydrobromic, hydroiodic, sulfuric, phosphoric, citric, lactic, maleic, acetic, benzoic, oxalic and related or similar acids. In many instances, the resulting salt crystallizes out of a suitable concentrated solution on chilling or standing or may be precipitated by addition of a solvent, such as ether or benzene in which the salt is insoluble.

The invention is characterized in that the Leuckart reaction is used for preparation of the compounds. In this process, the corresponding primary or secondary amine (that is, a compound as in Formula I above, except that R₂ and/or R₃ is hydrogen) is contacted with an organic acid and an aldehyde of the group R₂ or R₃ for reductive alkylation to form a compound according to Formula I. Preferably, the organic acid is formic acid.

The starting primary or secondary amines can be produced by the methods disclosed in application Ser. No. 231,018, filed Oct. 16, 1962, and now abandoned and assigned to the assignee hereof.

EXAMPLE I

N,N-methyl cyclohexyl-2-ethyl-3,3-diphenyl-propene-(2)-yl-amine-hydrochloride.

40 6.4 g. of N-cyclohexyl-2-ethyl-3,3-diphenyl-propene-(2)-yl-amine are treated under cooling with 2.3 g. formic acid and 0.25 ml. water. Further, 1.9 ml. aqueous formic aldehyde solution are added (35%), and the mixture heated for 15 hours to 110° C. After the cooling, the material is acidified with 9 ml. concentrated hydrochloric acid and distilled in vacuum until dry. The residue is treated with diluted soda lye, extracted with ether, and the ether part dried with sodium sulfate and distilled. The residue is dissolved in methanolic hydrochloric acid, and through addition of ether is obtained the N,N-methyl-cyclohexyl-2-ethyl-3,3-diphenyl-propene-(2)-yl-amine hydrochloride crystalline.

55 Melting point: 170-173° C. Yield: 80% of the theory.

EXAMPLE 2

N,N-dipropyl-2-ethyl-3,3-diphenyl-propene-(2)-yl-amine-hydrochloride

60 4.7 g. of 2-ethyl-3,3-diphenyl-propene-(2)-yl-amine are added under cooling to a mixture of 4.6 g. of formic acid and 0.5 ml. water. One adds 3.2 ml. propionic aldehyde and heats the mixture for 15 hours to 110° C. After the cooling 18 ml. concentrated hydrochloric acid are added and the excess formic acid and the excess propionic aldehyde is distilled off in vacuum. The residue is made alkaline, extracted with ether, and the separated ether part, dried with sodium sulfate, and distilled. The residue is dissolved in methanolic hydrochloric acid and through addition of ether is obtained the N,N-dipropyl-2-ethyl-3,3-diphenyl-propene-(2)-yl-amine hydrochloride.

Melting point: 221-222° C.

EXAMPLE 3

N,N-dimethyl-2-ethyl-3,3-diphenyl-propene-(2)-yl-amine hydrochloride

14.1 g. of 2-ethyl-3,3-diphenyl-propene-(2)-yl-amine are added under cooling to a mixture of 13.8 g. formic acid and 1.5 ml. water. To the reaction mixture are added 11.4 ml. of 35% aqueous formaldehyde solution, and the whole subsequently heated for 15 hours to 110° C. After the cooling one acidifies with 54 ml. concentrated hydrochloric acid, and the excess formic acid/formaldehyde solution is distilled-off in vacuum on the water bath. The residue is made alkaline with soda lye, extracted with ether, the separated ether part dried with sodium sulfate and distilled. There remains only an oil, which is dissolved in methanolic hydrochloric acid. Through addition of ether to the solution, the hydrochloride of the N,N-dimethyl-2-ethyl-3,3-diphenyl-propene-(2)-yl-amine crystallizes out.

Melting point: 198-200° C. Yield: 84% of the theory.

Other 2-alkyl, such as 2-propyl derivatives can be made by the procedure of the examples by corresponding change in the starting material.

UTILITY DATA

Compounds of Formula I

The effect on blood pressure in cats under urethane chloralose narcosis was noted.

N,N-dimethyl-2-ethyl-3,3-diphenyl - propene - (2) - yl-amine as hydrochloride, gluconate, nicotinate or methane sulfonate:

1 mg./kg. I.V.: Blood pressure increase of 15-20 mm. Hg, lasting about 30 minutes;

2 mg./kg. I.V.: Blood pressure increase of 25-40 mm. Hg, lasting about 1 to 2 hours.

N,N-dipropyl-2-ethyl-3,3-diphenyl - propene - (2) - yl-amine as hydrochloride, gluconate, nicotinate or methane sulfonate:

1 mg./kg. I.V.: Blood pressure increase of 20-30 mm. Hg, lasting about 1 hour.

2 mg./kg. I.V.: Blood pressure increase of 30-60 mm. Hg, lasting about 1½ to 4 hours.

For lower starting blood pressure the blood pressure increase effect is stronger and lasts longer than for normal or high starting blood pressure.

Under equal test conditions, for example, the 1-(3-hydroxyphenyl)-1-hydroxy-2-N-ethyl-amino - ethane - hy-

drochloride, in a dosage of 1-4 mg./kg., a blood pressure increase of 20-60 mm. Hg, lasting 4 to 8 minutes, is found.

Correspondingly, ephedrine effects in a dosage of 1-3 mg./kg., a blood pressure increase of 20-5° mm. Hg, which lasts up to about 40 minutes maximum.

COMPOSITIONS

The compounds may be given in dosage form hypodermically or intramuscularly in the form of HCl salt, or in the form of their salts in isotonic physiologically acceptable solutions, as for example water saline or peanut oil. Locally, they may be used in solution as a spray and in ointment.

The exact dosage in each instance is entirely dependent on the effect sought to be achieved, the mode of administration employed and the degree of caution which must be observed. In any instance, there is employed at least that amount of the compounds, i.e., active agent, necessary to produce the desired physiological effect, but less than that amount producing an undesired toxic effect.

The compounds of the invention, as can be readily appreciated, also constitute valuable tools for use in medical research, as for instance in connection with animal experiments and in particular in the study of their effect on the blood pressure by stimulating the contraction of the muscular tissue of the capillaries and arterioles.

What is claimed is:

1. N,N-methylcyclohexyl-2-ethyl-3,3-diphenyl-propene-(2)-yl-amine and medicinally acceptable salts thereof.

UNITED STATES PATENT OFFICE Giulini 212,5
CERTIFICATE OF CORRECTION FMM/na
Feb. 6, 19

Patent No. 3,489,760

Dated January 13, 1970

Inventor(s) Horst Eissler

It is certified that error appears in the above-identified patent and that said Letters Patent are hereby corrected as shown below:

1. Col. 2, line 8 cancel "ethyl-3,3...medicinally" and insert therefore --The salts are desirably hydrochlorides or medicinally--.
2. Col. 4, line 5, change "20-5°" to --20-50--.
